BAG AND SACK CLOSING DEVICE

Gilbert Hankel, Grant, Nebr.

Application April 12, 1934, Serial No. 720,339

3 Claims. (Cl. 150—6)

This invention relates to bag and sack closing devices, and has for its object the production of a simple and efficient means for facilitating the automatic closing of the mouth of the bag, and 5 also the locking of the bag in a closed position.

A further object of this invention is the production of a simple and efficient means for facilitating the drawing of the mouth of a bag to a closed and tightly fitting position and at the 10 same time efficiently locking the mouth of the bag in this closed position.

A still further object of the invention is the production of a simple and efficient locking means for a bag closing device wherein the locking means comprises a rotating knob member having a cam slot formed therein in which fits a pin for drawing the supporting frame of the mouth of a bag to a closed and locked position.

With these and other objects in view, which 20 will be hereinafter apparent, the invention consists in general of certain novel details of construction and combination of parts hereinafter fully described, illustrated in the accompanying drawing, and specifically claimed.

25 In the drawing:

Figure 1 is a top plan view of the bag closing device, a portion of the bag being broken away to show the structure of the supporting frame;

Figure 2 is a perspective view of the bag showing 30 the improved closing means in an open position, a portion of the bag being shown in section;

Figure 3 is a top plan view of the bag and closing means therefor in a closed position, a portion of the bag being shown in section;

Figure 4 is a side elevation of the locking means forming a part of the bag closing device;

Figure 5 is a top plan view of the structure shown in Figure 4;

Figure 6 is a section taken on line 6—6 of 40 Figure 5;

Figure 7 is an enlarged section taken on line 7—7 of Figure 1;

Figure 8 is a fragmentary perspective view of 45 one end of one of the bag closing arms which is adapted to support the locking rotating member or knob and illustrating the pin guiding slot formed in one end of the said arm.

By referring to the drawing it will be seen 50 that 10 designates the bag which is provided with an open mouth or outer end 11 in which outer end is mounted a closing frame 12 which closing frame preferably consists of four substantially similarly constructed members 13, 14, 55 15, and 16, which are pivotally connected at

their adjoining ends, as at 17 to form the rectangular frame 12 when in an open or extended position.

The members 13 and 16 are pivotally connected at their outer ends by means of a journal pin 18 having a washer 19 at one end and a head 20 at its other end. A coil spring 21 is coiled around the pin 18, and this coil spring is provided with extending end portions 22 and 23, the end portions 22 and 23 being provided with right 10 angularly extending loops 24 and 25, which loops 24 and 25 are coiled about or around the members 13 and 16, as shown clearly in the drawing to provide an anchoring means for the outer extending ends 22 and 23 of the coil spring 21. 15 These end portions 22 and 23 are of material length and extend approximately one-half the length of the members 13 and 16, as shown. These projecting ends 22 and 23 are adapted to exert an outward expanding action upon the 20 members 13 and 16 to normally force these members 13 and 16 to a spread-apart or open position.

The members 14 and 15 are similarly connected in the manner previously described with respect to the members 13 and 16 by means of 25 a pivot pin 26 about which is coiled a coil spring 27 having projecting ends 28 and 29 similar to the projecting ends 22 and 23 previously described. These projecting ends 28 and 29 are connected to the members 14 and 15 by means of 30 the right angularly extending coils 30 and 31 similar to the right angularly extending coils 24 and 25 previously described. By means of these springs 21 and 27 it will be seen that these 35 springs will tend to force the members 14 and 15, and 13 and 16 apart, or to an open position to normally hold these members in a spread-apart condition to provide a rectangular supporting frame for the mouth of the bag 10 when the outer end of the bag is unlocked or 40 open. The adjoining ends of the members 13 and 14 are connected by means of a pivot pin 32 which pivot pin 32, as shown in Figure 6, is provided with a headed portion 33 projecting above the pivotally connected ends of the members 13 45 and 14. A suitable washer 34 is carried by and secured to the pin 32 and rests upon the top of the overlapping end portions of the sections or members 13 and 14.

The member 16 is provided at its end opposite 50 the pivot pin 18 with a laterally extending flattened plate 35 which extends inwardly of the frame 12, as shown in the drawing, when the bag is closed, this flattened plate 35 having a bifurcated or notched portion 36 to receive the pin 32 55

when the frame 12 is drawn to a closed position, such as is shown in Figures 3 and 5.

A rotating knob 37 is carried by the journal pin 38 which constitutes a pivotal connection between the adjoining or overlapping ends of the members 13 and 16 and this knob 37 carries an eccentric plate 39, which eccentric plate projects to one side of the knob and is provided with a cam or eccentric slot 40 extending from a point near the center of the plate 39 to the outer edge thereof, as shown clearly in Figure 5. This slot 40 is provided with an enlarged inner end 41, as shown in Figure 5, to receive the pin 32 when the bag is in its locked position. The outer or open end of the bag 10 may be folded over the members 13, 14, 15 and 16 and stitched, as at 42, to protect the members of the frame 12, the pin 32 projecting through a suitable notch 43 and the pin 38 which supports the knob 37 projecting through a suitable notch formed in the fabric of the bag. The flattened plate 35, as well as the knob 37 and eccentric plate 39, extends above the upper end of the bag, as shown in Figure 2. The head 33 of the pin 32 will tend to hold the pin 32 from jumping out of the slot 40.

The plate 39 is provided with apertures 41a located upon opposite sides of the outer end of the slot 40 through which apertures may extend a suitable wire seal 42.

The operation of the device is as follows:—

The outer end of the bag will be normally held in its open position, as shown in Figure 2, due to the action of the springs 21 and 27. This will facilitate the filling of the bag or the removal of the contents from the bag. However, when it is desired to close the bag, the members 15 and 16 of the frame 12 are forced to a closed position with respect to the members 13 and 14 so as to cause the members to extend in substantially parallel relation, as shown in Figure 3. The pin 32 will extend into the notch 36 of the plate 35 and by rotating the knob 37, the cam slot 40 will be moved into contacting engagement with the pin 32 for drawing the pin 32 longitudinally of the slot 40 and toward the pivot pin 38, which action will tightly draw the sections 15 and 16 toward the sections 13 and 14 of the frame 12, and thereby constitute an efficient locking means for holding the sections of the frame 12 in their closed relation.

When it is desired to open the bag, the knob 37 is operated or rotated in a counter-clockwise

direction for moving the pin 32 out of contact with the slot 40, whereupon the springs 21 and 27 will immediately force the sections of the frame 12 to an open position.

The present device is especially adapted for use in connection with grain, flour, sugar, and tobacco bags, and the like.

Having described the invention, what is claimed as new is:

1. A bag closing device of the class described comprising a plurality of pivotally connected members adapted to be mounted in the mouth of a bag and capable of moving to a position to open or close the mouth of a bag, a pin carried by one of said members, an eccentric locking device engaging said pin for drawing the members to a closed position, and guiding means carried by one member and engaging said pin for holding said pin and members against lateral shifting movement and in contact with said cam locking member as the eccentric locking device draws said pin and members to a closed position.

2. A bag closing device of the class described comprising a plurality of pivotally connected members adapted to be mounted in the mouth of a bag and capable of moving to a position to open or close the mouth of a bag, a pin carried by one of said members, an eccentric locking device engaging said pin for drawing the members to a closed position, and a slotted plate carried by one member and extending across said eccentric locking device for receiving said pin and holding the pin and members against lateral shifting movement as said eccentric locking device draws said pin and members to a closed position.

3. A bag closing device of the class described comprising a plurality of pivotally connected members adapted to be mounted in the mouth of a bag and capable of moving to an open and a closed position, a pin carried by one of said members, a locking device rotatably mounted upon one of said members and having an eccentric slot adapted to engage said pin for drawing said pin within said eccentric slot as said locking device is rotated, and a slotted plate carried by one of said members and being adapted to extend across said eccentric slot as said locking device is rotated and also being adapted to receive said pin for holding said pin against lateral shifting movement as the pin is being drawn within said eccentric slot.

GILBERT HANKEL.
